UNITED STATES PATENT OFFICE.

LEO GUDEMAN, OF NEW YORK, N. Y.

DESIGN FOR A FLUID-RECEIVING RECEPTACLE.

58,290.

Specification for Design.

Patented July 5, 1921.

Application filed September 29, 1920. Serial No. 413,621. Term of patent 3½ years.

To all whom it may concern:

Be it known that I, LEO GUDEMAN, a citizen of the United States, residing at New York city, in the county of New York and State of New York, have invented a new, original, and ornamental Design for Fluid-Receiving Receptacles, which is adapted to be placed on electric light bulbs, of which the following is a specification, reference being had to the accompanying drawing, forming a part thereof.

Figure 1 is a perspective view of a fluid

receiving receptacle showing my new design, and Fig. 2 is a substantially vertical sectional view showing the parabolically formed interior wall of my new design.

I claim:—

The ornamental design for a fluid receiving receptacle, as shown.

LEO GUDEMAN.
